UNITED STATES PATENT OFFICE

100,715

DESIGN FOR A STORM CURTAIN

Leslie C. Newland, Marshalltown, Iowa

Application May 21, 1936, Serial No. 62,760

Term of patent 14 years

To all whom it may concern:

Be it known that I, Leslie C. Newland, a citizen of the United States, residing at Marshalltown, in the county of Marshall and State of Iowa, have invented a new, original, and ornamental Design for a Storm Curtain, of which the following is a specification, reference being had to the accompanying drawing, forming part thereof.

I claim:—

The ornamental design for a storm curtain as shown.

LESLIE C. NEWLAND.
